UNITED STATES PATENT OFFICE.

ROBERT L. DORAN, OF CHICAGO, ILLINOIS, ASSIGNOR OF THREE-FOURTHS
TO JAMES S. KNIGHT AND J. H. TALBOT MARTIN, OF CHICAGO, ILLINOIS,
AND MATTHEW C. MCGANNON, OF NASHVILLE, TENNESSEE.

DESIGN FOR A GAS-LAMP.

SPECIFICATION forming part of Design No. 35,787, dated March 4, 1902.

Application filed January 30, 1902. Serial No. 91,945. Term of patent 7 years.

To all whom it may concern:

Be it known that I, ROBERT L. DORAN, a citizen of the United States, residing at the city of Chicago, in the county of Cook and State of Illinois, have invented and produced a new and original Design for a Gas-Lamp, of which the following is a specification, reference being had to the accompanying drawing, forming a part thereof.

10 The drawing shows a side elevation of a gas-lamp embodying my design.

The leading or material feature of my design consists of a glass globe A, immediately beneath which is an inverted conoidal or pear-shaped base B, the lower portion of this base B being formed with openings b. At the extreme lower end of the base B is an acorn-shaped tip or ornament D. At the top of the base B is the ornamental band E, and between the band E and the bottom of the globe

A is a band F, having a slightly-flaring upper edge. Within the globe A is a cluster of gas-burners G, surmounted by mantles g. Upwardly from the center of the globe A extends a pipe H. Immediately above the globe 25 A is a concavo-convex canopy K of the usual circular form surmounted by a crown-shaped ornamental band L. At a distance above the band L is a disk-shaped canopy M, also of the usual circular form. 30

Having thus described my invention, what I claim as new, and desire to secure by Letters Patent, is—

The design for a gas-lamp as herein shown and described.

ROBERT L. DORÁN.
